UNITED STATES PATENT OFFICE.

JOHN L. CONAWAY, OF PHILADELPHIA, PENNSYLVANIA.

UMBRELLA RIB AND STRETCHER.

SPECIFICATION forming part of Letters Patent No. 599,416, dated February 22, 1898.

Application filed July 28, 1897. Serial No. 646,177. (No model.)

To all whom it may concern:

Be it known that I, JOHN L. CONAWAY, a citizen of the United States, residing in the city and county of Philadelphia, State of Pennsylvania, have invented a new and useful Improvement in Umbrella Ribs and Stretchers, which improvement is fully set forth in the following specification and accompanying drawings.

- 10 My invention relates to improvements in ribs and stretchers for umbrellas and kindred articles, and has for its object not only to strengthen the said parts and the frame, but to enable the said frame to fold closer and 15 eliminate all danger of tearing or otherwise damaging the cover and avoid piecing of the rib and the employment of sleeves and other appliances for the bearing of the pivots or axes of the stretchers.
- 20 Figures 1 and 2 represent side elevations of an umbrella rib and stretcher embodying my invention. Fig. 3 represents a longitudinal section thereof. Fig. 4 represents a transverse section on line $x x$, Fig. 3. Fig. 5 represents a sectional view on the line $y y$ of Fig. 3.

Similar letters of reference indicate corresponding parts in the figures.

Referring to the drawings, A designates a 30 rib formed of a strip of metal or other suitable material formed partly into a U or trough shaped section or what may be termed "channeled" and partly into tubular form.

B designates a stretcher composed of two 35 sections B' and B², which are formed at their adjacent ends with eyes C, through which is passed the pivotal pin D, as shown in Figs. 1 and 3, the ends of said pin being riveted or headed in place. These sections are preferably formed of solid metal and cylindrical in shape, particularly section B', or they may be otherwise, as of the U or trough shape, particularly section B², and this section B² is flattened and eyed, as shown at E, in the usual 40 manner, for the purpose of attaching the stretcher to the runner. The section B' is placed as a stationary piece or fixture within the channel of the upper half of the rib A, as shown in Fig. 3, and so as to be entirely 45 inclosed by the said rib, as shown in Fig. 5, the junction of the sections being inclosed

within the said channel. The upper end of the rib is flattened and eyed, as well as the end of the section B' of the stretcher, as shown at F, Fig. 3. While this form is preferred, 55 it would not depart from the essence of my invention to avoid extending the stretcher-section B' the full length of this half of the rib and not flattening and eyeing the said stretcher-section. The result of the former 60 construction is that the rib and said stretcher-section B' are practically one and the same piece. The section B² (or the stretcher proper) is left free to swing as usual, and when the frame or the umbrella is closed the said section, being preferably of the same dimension 65 as the channel of the rib, settles into and fits snugly within said channel, as shown in Fig. 4.

Heretofore a stretcher has been formed of a single piece or section which is pivotally attached directly to the rib by a pin or eye-joint. For the purpose of more securely holding the stretcher, as well as strengthening the rib at this point, it has been usual to affix a cleat or sleeve to the rib or some other 70 means adopted, which rendered the rib bulky and unsightly and very apt to tear or damage the covering of the umbrella. To avoid this tearing by the junction, the same has been covered with suitable material, or, more 75 properly speaking, "ragged." Another detriment of the frames now in use is the difficulty of securing an entire disappearance of the stretcher at the junction within the rib and at the same time strengthen the frame. 80 By my construction these difficulties are overcome. By making the stretcher in two sections, sinking and inclosing one section into a portion of the rib, flattening the end of the rib and stretcher thus inclosed, the 85 said rib is not only very materially strengthened, but it avoids the necessity of attaching the stretcher proper directly to the rib at all, and no junction whatever is observable. No ragging or strengthening of said joint is 90 needed. The cover of the umbrella is free from danger from such a source and the probability of the rib and stretcher becoming parted or the connections dipping is reduced 95 to a minimum.

100 As has been stated, the rod or section B' is inclosed throughout its entire length in the

- tubular portion of the rib, this constituting the means of connecting the stretcher proper with the rib, while it also reinforces the latter, since the tubular portion of said rib acts 5 as a sheath or wrapper, having the section B' within it as a core, the reinforcing effect of which is evident. Again, the section B' and tubular portion of the rib have coincident eyes with which the collar of ordinary 10 construction (not shown) may be connected, thus assisting to prevent any possible shifting of the core or section B' in the tubular portion of the rib, whereby the strength of the reinforced rib is preserved.
- 15 By constructing the other section of the stretcher of cylindrical metal no larger or of greater diameter than the channel of the rib the said stretcher is enabled to entirely disappear within said channel and the umbrella 20 rendered capable of being tightly closed or rolled into a small compass.

Attention is directed to the fact that one section of a stretcher is held by the corresponding portion of the rib as the means for 25 connecting the stretcher with said rib, thus avoiding the use of a sleeve and piercing of the rib for the connection of the stretcher with the rib, as heretofore practiced, it being also noticed that the pivot or axis of the sections

of the stretchers are inclosed by the adjacent 30 portion of the rib and practically concealed.

Having thus described my invention, what I claim as new, and desire to secure by Letters Patent, is—

1. As a new article of manufacture, a rib 35 for an umbrella or kindred article, formed partly of a tubular and partly of a channeled portion, a rod or section inclosed in said tubular portion and a stretcher pivoted to said rod, the joint between said stretcher and rod 40 being located within said channeled portion so that said stretcher will lie in said channeled portion when the umbrella is closed.

2. As a new article of manufacture, a rib 45 for an umbrella or kindred article, formed partly of a tubular and partly of a channeled portion, a rod or section inclosed in said tubular portion and a stretcher pivoted directly to said rod, the walls of said channeled portion covering the pivotal connection common 50 to said stretcher and rod, and the adjacent ends of said section and rib having coincident eyes.

JOHN L. CONAWAY.
